FLUID DISPENSING DEVICE

Herman W. Fisher, Philadelphia, Pa.

Application May 3, 1933. Serial No. 669,137

8 Claims. (Cl. 15—134)

The present invention relates to a fluid dispensing device which is particularly useful in handling a cleansing fluid such as gasoline.

The primary object of the invention is to provide a fluid dispensing device, specifically a bottle with a closure member or cap therefor, by means of which a cleansing operation can be performed without removing the cap simply by turning it slightly to permit egress of fluid upon inversion of the bottle and then rubbing the spot to be cleaned with a pad of felt or other similar material affixed to the top of the closure member.

A more detailed recitation of the objects of my invention includes (1) the provision of a bottle having a cap which can be rotated in one direction to seal the bottle against egress of fluid and in the other direction to permit discharge of a limited quantity of the fluid which is just sufficient for convenient application in a cleansing operation; (2) the provision of a device of the character described in which adequate distribution of the fluid over the area of the cleaning pad may be effected; (3) the provision of a cleaning bottle of the character mentioned in which the cap or closure member is non-removable so that the bottle cannot be refilled without distorting or impairing the usefulness of the cap; (4) the provision of a device of this character which is of simple yet sturdy construction, easy to manufacture, and reasonable in cost.

The nature of the invention and its objects will be more clearly apparent and better understood in connection with the following description of the accompanying drawing, wherein—

Fig. 1 is a vertical section through the upper portion of a bottle equipped with my improvements showing the cap in the position which it assumes when the bottle is tightly closed.

Fig. 2 is a side elevation of the upper portion of my improved device taken in a direction at right angles to the section of Figure 1, but with the outer protecting cover removed.

Fig. 3 is a side elevation of the neck portion of my improved bottle taken at right angles to the elevation shown in Fig. 2 and with a portion of the neck broken away to illustrate certain features of the construction in section.

Fig. 4 is a plan view of the neck of the bottle.

Fig. 5 is a section of the neck of the bottle with the cap in place showing the position which the latter occupies during a cleansing operation.

Fig. 6 is a plan view of the closure member or cap used with my invention, and

Fig. 7 is a view of the under face of the cap shown in Fig. 6.

In connection with Figs. 1 and 5, I should like to point out that the sections illustrated in these figures are taken approximately as indicated by the section line with the arrows appearing in Fig. 4, although it will be understood, of course, that the cap in Fig. 1 occupies a different circumferential position than it does in Fig. 5.

Referring to the drawing it will be seen that the neck portion 8 of the bottle 9 is provided across its top with a substantially flat web portion 10 in which is formed the eccentrically disposed aperture 11 through which the cleaning fluid can be discharged when the cap is in position to permit such discharge, as will appear hereinafter.

At its upper margin the neck is provided with a shoulder or bead 12 which is cut away at two diametrically opposite points to provide the channels or grooves 13.

Just below the shoulder 12 there is formed on the neck a pair of oppositely disposed sections 14 of a right hand cam 14 and a similar pair of oppositely disposed sections of a left hand cam 15. Adjacent sections 14 and 15 meet in a stop shoulder 16 and extend substantially half-way around the neck of the bottle so that each section 14 occupies roughly only one-quarter of a circumference and each section 15 another quarter of the circumference. However, there are two right hand sections 14 located at diametrically opposite points, as well as two left hand sections 15 also diametrically disposed to occupy substantially the other two quarters of the circumference. Adjacent sections 14 and 15 terminate at points substantially 180° apart so as to provide the vertical channel or groove 13a at each side of the bottle, which channels are, in effect, continuations of the channels 13 formed in the bead or shoulder 12. The effect of the arrangement is to provide the bottle neck with what may be termed a half-right-half left hand cam surface.

The closure member or cap used in connection with my improved dispensing device includes a cup-shaped sealing member 17, the side wall or skirt 18 of which fits down around the top of the neck of the bottle in order to embrace the shoulder 12 and the cams 14 and 15.

At two diametrically opposite points the skirt 18 is provided with the indent 19 which, when the cap is placed in position, are adapted to fit into the slide through the vertical grooves or

channels 13, 13a. Upon subsequent rotation of the cap it will be clearly understood that the indents 19 will engage beneath the cams 14 when the cap is turned in one direction and beneath the cams 15 when the cap is turned in the opposite direction. In either direction, however, it is obvious that the cap will be tightly held against the top of the bottle in order to prevent leakage.

10 Interiorly the cap is provided with any suitable type of washer or gasket member 20, preferably of cork.

15 Eccentrically disposed but located on the diameter which passes through the two indents 19 the cup-shaped cap 17 is provided with a relatively restricted discharge orifice or outlet 21, and the gasket member 20 is provided with a suitable aperture 22 adapted to register therewith, although the aperture 22 may be of larger diameter if desired. In fact I prefer to make the aperture 22 of a diameter substantially corresponding to the diameter of the discharge opening 11 in the web 10 of the bottle neck. The gasket member 20 may be held in place in any 25 suitable or desired manner.

30 The cap member is also provided with a dome-shaped supporting plate 23 having a plurality of perforations 24, which plate serves as a backing member for the cleaning pad 25. The pad may be made of felt or any other porous and absorbent material suitable to the purpose.

35 The lower edge of the plate 23 is bent outwardly and upwardly around the edge of the felt 25, as indicated at 26, and by crimping in the outermost edge slightly as shown at 27, the cleaning pad can be very effectively held in position. The construction of the plate 23 is such as to provide a relatively large distributing chamber 28 between the flat top of the cap 17 and the pad 25 40 which serves to distribute the cleaning fluid, as will appear below in connection with a description of the manner in which the device is used. The cap 17 and the backing plate 23 may be secured together in any desired manner, as by 45 welding shown at 29.

50 The lower portion of the neck of the bottle is provided with the threads 30 over which is screwed the cover member 31, the latter serving as a means for keeping the device in clean condition when not in use.

55 After the bottle is filled with the cleaning fluid the cleaning cap or closure member is placed in position with the indents 19 fitting into the vertical recesses or grooves 13, 13a. Then, by rotating the cap in the direction of the arrow 32 in Fig. 6, the opening 22 in the cork gasket 20 will be brought to the dot and dash position shown at 22a. In this position the indents 19 have passed under the right hand cams 14 which 60 serve to hold the cap in tight position against the top of the bottle so as to seal the opening 11. By turning the cap 19 in the direction of the arrow 33 in Fig. 6 the opening 22 can be brought to the dot and dash position 22b where it will 65 register with the opening 11 in the web 10 of the bottle. During this motion the indents 19 engage the under surface of the left hand cams 15, and when the openings 22 and 11 are in registry the gasket 20 is tightly pressed against the top of 70 the bottle in order to prevent leakage laterally between the cap and the top web of the bottle, egress of fluid during a cleaning operation, taking place, of course, through the openings 11, 22 and 21.

75 When the bottle is inverted for a cleaning

operation the fluid enters the distributing chamber 28 from which it passes through the perforations 24 into the cleaning pad 25. A gentle rubbing motion will serve to scatter the cleansing fluid as it enters the chamber 28 so that it will be substantially uniformly distributed throughout the cleaning pad.

80 Fig. 2 shows the cap with the indents 19 in the vertical channels 13, 13a, and in this position the side wall or skirt 18 of the cap may be crimped in at the sides intermediate the indents 19 as indicated at 34. The crimped portions 34 will extend beneath the shoulder 12. It will be seen, therefore, that once the cap has been applied it is non-removable and the bottle is non-refillable unless, of course, the cap is mutilated and its usefulness impaired.

85 I claim:—

1. The combination of a fluid dispensing container having a neck with a top web and an eccentrically disposed aperture therein, a half-right-half-left hand cam surface on the neck, and a cap having a correspondingly disposed aperture, said cap being provided with means for engaging said cam surface and all of said parts being constructed and arranged so that by turning the cap in one direction it will be tightly pressed against the top web with the apertures in alignment and by turning it in the other direction it will be tightly pressed against the top web to seal the aperture in the web and prevent egress of the container contents.

90 2. A fluid dispensing container having a neck with a top web and an eccentrically disposed aperture therein, an external bead around the top of the neck with a pair of diametrically disposed slots cut therein, a section of a righthand cam below the bead to one side of each slot, a section of a left hand cam below the bead to the other side of each slot, a cap having means fitting said slots and adapted to engage said cam upon rotation of the cap, and an eccentrically disposed aperture in the cap, said cap, when turned in one direction, seating itself against the top web with the apertures in alignment and when turned in the other direction seating itself against the top web to seal the aperture in the web and prevent egress of the container contents, the metal of the cap skirt being crimped under the bead at a pair of diametrically opposite points between the means which fits the slots and engages the cams.

95 3. A fluid dispensing device including in combination, a container having a neck with a substantially flat web across its mouth, an eccentrically disposed aperture in said web, oppositely disposed sections of right and of left hand cam surfaces below the margin of the neck on the outside thereof, a retaining bead or shoulder at the margin above said cam surfaces, a vertical channel formed in the cam surfaces and in the shoulder at two diametrically opposite points, and a cap member having a pair of indents in its skirt portion adapted to fit said channels and, upon rotation, engage the cam surfaces, said cap having an aperture adapted to register with the web aperture when the cap is rotated so that the indents engage one of said cam surfaces and to seal itself against the web when the cap is rotated so that the indents engage the other of said cam surfaces, the metal of the skirt being crimped under the bead intermediate the indents whereby the cap is non-removable without mutilation thereof.

100 4. A fluid dispensing container having a top web and a half-right half-left hand cam surface therebelow together with an eccentrically disposed

- aperture in the top and a cap with a correspondingly disposed aperture adapted to align with the web aperture when the cap is turned in one direction, said cap sealing the web aperture when the 5 cap is turned in the opposite direction.
5. The device of claim 4 including a retaining bead on the container and means on the cap engaging said bead to prevent removal of the cap after initial assembly.
- 10 6. A fluid dispensing container having a neck with a half-right-half-left hand external cam surface together with means providing an eccentrically disposed aperture therethrough and a cap with a correspondingly disposed aperture adapted 15 to align with said first aperture when the cap is turned in one direction, said cap sealing said first aperture when the cap is turned in the opposite direction.
7. The device of claim 6 including a retaining 20
8. The combination of a container having a neck with means providing an eccentrically disposed aperture therethrough, a half-right-half-left hand cam surface on the neck, and a cap also having an eccentrically disposed aperture adapted to cooperate with said first aperture, said cap being provided with means for engaging said cam surface and all of said parts being constructed and arranged so that by turning the cap in one direction it will be tightly pressed against the top with the apertures in alignment and by turning it in the other direction it will be tightly pressed against the top to seal said first mentioned aperture and prevent egress of the container contents. 25
